SHEET METAL WORKING HAMMER

Robert A. Daniels, Santa Barbara, Calif.

Application July 11, 1950, Serial No. 173,103

3 Claims. (Cl. 81—15)

1

This invention relates to improvements in sheet metal working hammers and more particularly to a hammer for shrinking stretched portions of a sheet metal structure, such as an automobile body or fender.

It is among the objects of the invention to provide an improved sheet metal working hammer which is effective, when applied with sufficient force to a stretched area of sheet metal, to work or knead the sheet metal and produce a shrinking effect on the area treated, which may be used with equal effect on either flat or curved areas and may be used with or without a backing dolly, as conditions may require, which will reduce a dented area in an automobile body or fender to the original shape by shrinking the stretched metal and by drawing low spots up to the original contour and will leave the surface sufficiently smooth that filling and filing of the reworked surface is unnecessary and a paint receiving surface can be provided by polishing the area with a suitable abrasive, which requires only the usual skill of an automobile body repairman, and which is simple and durable in construction, and positive and effective in use.

Other objects and advantages will become apparent from a consideration of the following description and the appended claims in conjunction with the accompanying drawing, wherein:

Figure 1 is an end elevational view of a sheet metal working hammer illustrative of the invention;

Figure 2 is a side elevational view of the hammer illustrated in Figure 1;

Figure 3 is a plan view of one of the working faces of the hammer;

Figure 4 is a magnified area of the plan view illustrated in Figure 3;

Figure 5 is a fragmentary cross sectional view on an enlarged scale taken substantially on the line 5—5 of Figure 4; and

Figure 6 is a fragmentary cross sectional view on an enlarged scale taken substantially on the line 6—6 of Figure 4.

With continued reference to the drawing, the hammer comprises a head 10 formed of suitable metal, such as iron or steel, and including a centrally located, handle receiving eye formation 11 and two stems 12 and 13 of generally cylindrical shape joined at adjacent ends to the respectively opposite sides of the eye formation 11 and extending in opposite directions from the eye formation along a common center line. At its end remote from the eye formation 11 the stem 12 is laterally extended to provide an enlarged nose

2

14 of rectangular shape and at its end remote from the eye formation the stem 13 is laterally extended to provide an enlarged nose 15, also of rectangular shape.

5 A handle 16 is secured at one end in the eye formation 11 and extends from this eye formation with its center line substantially perpendicular to the common center line of the two stem portions 12 and 13.

10 The two rectangular nose formations 14 and 15 have a width of approximately one inch and a length of approximately two and one half inches and are so arranged that their longer dimensions extend along the handle 16. The common center line of the stem portions 12 and 13 intersect the longitudinal center lines of the two nose formations at a location spaced approximately one and one-eighth inch from the ends of the nose formations extending outwardly of the end of the eye formation 11 opposite that from which the handle extends and approximately one and three-eighths inches from the ends of the nose formations adjacent the end of the handle remote from the eye formation 11.

15 20 The total length of the hammer head is approximately five inches and the weight of the hammer head approximately one and one-quarter pounds.

25 The nose formation 14 is provided on its outer side with a flat working surface 17 which is substantially perpendicular to the common center line of the stem portions 12 and 13 and the nose formation 15 is provided on its outer side with a working surface 18 which is transversely curved to a partly cylindrical shape. This working surface 18 is longitudinally perpendicular to the common center line of the stem portions 12 and 13 and the transverse curvature of this working surface is symmetrically related to this common center line.

30 35 40 The nose formation 14 is provided with a series of small, contiguous teeth, as indicated at 20 in Figures 4 and 5, covering the entire area of the corresponding working surface. The nose formation 15 is provided on its outer side with a flat working surface 17 which is substantially perpendicular to the common center line of the stem portions 12 and 13 and the nose formation 15 is provided on its outer side with a working surface 18 which is transversely curved to a partly cylindrical shape. This working surface 18 is longitudinally perpendicular to the common center line of the stem portions 12 and 13 and the transverse curvature of this working surface is symmetrically related to this common center line.

45 Each of the working surfaces 17 and 18 is provided with a series of small, contiguous teeth, as indicated at 20 in Figures 4 and 5, covering the entire area of the corresponding working surface.

50 In a hammer specially designed for working sheet metal of the gauge commonly used in automobile body and fender work, as described above, these teeth have a height of approximately one thirty-second of an inch and a size such that approximately two hundred and fifty teeth are included in each square inch of working surface of the hammer.

The teeth are divided by grooves, as indicated at 21 and 22 in Figures 3 and 4, which extend diagonally of the rectangular working face areas

and mutually intersect each other. The teeth 20 are generally pyramidal in shape but are sloped more in one direction than in the other, as is clearly illustrated in Figure 5, and have elongated rather than pointed outer ends. The major slope 5 of the teeth is toward the ends of the working faces remote from that end of the handle which is remote from the eye formation 11. The mutually parallel grooves 22 extend entirely to the bottoms of the teeth but the grooves 21 extend 10 only about half way the height of the teeth from the outer ends thereof.

The size and weight of the hammer and the size and arrangement of the teeth 20 have been found to be critical within narrow limits for working sheet metal of particular gauges or thicknesses, the dimensions given above having been found to provide the most satisfactory results when used on sheet metal of the gauge commonly employed in automobile fender and body work.

By properly using the hammer, as described above, on a dented or stretched area of the automobile body or fender, the distorted or stretched metal can be reworked to shrink and draw it back to its original condition and the original contour can be obtained without leaving a rough surface which has to be filled in with solder or putty and then filed to the proper shape and without the necessity of welding or replacing the damaged portion of the structure. The hammer leaves the 30 work surface in a substantially smooth condition so that a paint receiving surface can be provided by merely polishing the reworked surface with an abrasive disc or with emery paper or other suitable abrasive.

In using the hammer the force of the blow is directed longitudinally of the working face in a direction away from the distal end of the handle as well as normal to the working face. By working first around the edge portion of a dent with 40 such downwardly and outwardly directed blows this portion of the dented material is worked back toward the undamaged portion of the structure and by gradually working toward the center of the dent all of the stretch in the damaged metal 45 can be removed as the dented area is restored to its original contour.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing de-

scription, and all changes which come within the meaning and range of equivalency of the claims are, therefore, intended to be embraced therein.

What is claimed is:

1. A sheet metal working hammer comprising a hammer head having a handle receiving eye formation and a working face spaced from said eye formation, said working face having contiguously arranged pointed teeth covering the entire area thereof, said teeth having a height of approximately one thirty second of an inch and a size such that there are approximately two hundred and fifty teeth on each square inch of working surface.

2. A sheet metal working hammer comprising a hammer head having a handle receiving eye formation and a working face spaced from said eye formation, said working face having contiguously arranged pointed teeth covering the entire area thereof, said teeth having a height of approximately one thirty second of an inch and a size such that there are approximately two hundred and fifty teeth on each square inch of working surface, and said hammer having a weight of approximately one and one-quarter pounds.

3. A sheet metal working hammer comprising a hammer head having a handle receiving eye formation and a working face spaced from said eye formation, and a handle secured at one end in said eye formation, said working face having contiguously arranged pointed teeth covering the entire area thereof, said teeth having a height of approximately one thirty second of an inch and a size such that there are approximately two hundred and fifty teeth on each square inch of working surface and having an inclination outwardly from the associated working face and away from the end of said handle remote from said eye formation.
